UNITED STATES PATENT OFFICE.

SOMA HERZOG, OF NEW YORK, N. Y.

TOY.

1,338,449.

Specification of Letters Patent. Patented Apr. 27, 1920.

Application filed September 15, 1919. Serial No. 323,846.

To all whom it may concern:

Be it known that I, SOMA HERZOG, a citizen of the United States, and a resident of the borough of Manhattan, city, county, and

5 State of New York, have invented certain new and useful Improvements in Toys, of which the following is a specification.

My invention relates to toys and has for its object to provide a toy consisting of one 10 or more components or figures capable of movements relatively to each other and to the other parts of the toy to produce various effects. A further object of my invention is to include in the toy, simple and efficient 15 actuating means whereby manipulation of the components thereof is brought about. My invention will be fully described hereinafter and the features of novelty will be pointed out in the appended claims.

20 In the accompanying drawings, which show several specific embodiments of my invention without defining its limits, Figure 1 is a sectional elevation of one form of toy; Fig. 2 is a cross-section thereof on the line 25 2—2 of Fig. 1; Fig. 3 is a fragmentary section of another form; Fig. 4 is a detail end view thereof, partly in section and Fig. 5 is a detail view of an actuating means forming part of my invention.

30 In its preferred form the toy comprises a carrying element or body mounted upon wheels and including one or more movable figures constructed to represent characters, human or animal, and of sufficient weight, 35 or weighted, to return to the normal position by gravity and actuated against the force of gravity by means of a lever or levers coöperating with actuating mechanism driven by the wheels of the body when the latter is in 40 motion.

In Figs. 1 and 2 the carrying element or body 10 is hollow and is mounted upon front wheels 11 and rear wheels 12 carried respectively by axles 13 and 14. The figures 15 45 and 16 comprising the movable elements, in this example of my invention, are fashioned in the form of galloping horses and are pivotally mounted at 17 upon a pivot block 18 secured upon the top 19 of the body 10 in 50 any suitable manner. The figures 15 and 16 are continued in the form of levers 20 which extend into the body 10 through slots 21 formed in said top 19 at the proper points. The levers 20 project into the circular paths 55 of pins 22 extending in opposite directions from and carried by a disk 23 secured upon

the axle 14 of the rear wheels 12 and partaking of the motion thereof; in the preferred arrangement the pins 22 are located upon the disk 23 in off-set relation to each other, 60 for instance, at points diametrically opposite to each other as shown. This form of toy may include in addition a figure 24 representing a driver seated upon a seat 25 which is secured upon the top 19 in any 65 convenient manner. The toy may further be provided with an eyelet 26 or equivalent device to which a cord or the like may be attached whereby said toy is propelled on the wheels 11 and 12. 70

In operation as the toy is caused to travel on its wheels 11 and 12, these will rotate in the customary manner and through the medium of the axle 14 will bring about a rotation of the disk 23. This causes the pins 22 75 to travel in circular paths and to periodically engage the levers 20 which, because of the camming action of the pins 22 thereon, are pivotally swung upon the pivot 17 which movement is communicated to the 80 horses 15 and 16 and imparts thereto a life-like galloping motion. Because of the off-set relation of the pins 22 upon the disk 23 the horses 15 and 16 are alternately actuated against the force of gravity. As the pins 22, after having exerted their camming action upon the levers 20 and in continuing their paths of travel move away from said levers, the latter under the weight of the 85 horses 15 and 16 are returned to normal position in contact with the axle 14, said horses at the same time reassuming their normal 90 positions. As the traveling movements of the pins are generally speaking fairly rapid the levers 20 will be quickly relieved from 95 the influence thereof and will, as a result, engage the shaft 14 with an audible blow. The alternate audible impacting of the levers 20 against the axle 14 thus produces the 100 audible effect of galloping horses, which effect is magnified and heightened because of the amplifying action of the hollow body 10, the top 19 of which may be said to act in the nature of a sound board. A very realistic result is thus obtained which adds to 105 the interest of the child in the toy and maintains its popularity far beyond that of the customary traveling toy which is silent with respect to any effects such as the above.

In Fig. 3 the lever 20^a corresponding to 110 the levers 20, depends from a figure 24^a representing a human being in a seated pos-

ture, said figure 24^a being pivoted at 17^a upon a pivot block 18^a mounted upon the top 19 of the body 10. The lever 20^a projects downwardly through a slot 21^a formed in 5 the top 19 and between two spaced disks 23^a and into the circular paths of a pair of pins 22^a extending between said disks for instance, at diametrically opposite points. The disks 23^a are carried upon the axle 14 10 and partake of the rotative movements thereof when the toy is propelled upon the wheels 12.

In this form, as the disks 23^a travel in their circular paths, the pins 22^a will successively engage the lever 20^a and by reason of the fact that they exert a camming action thereon, will cause the figure 24^a to be swung upwardly on the pivot 17^a. As the pins 22^a in continuing their travel move 20 away from the lever 20^a the figure 24^a will drop back to its normal position by gravity, the lever 20^a partaking of this movement and likewise resuming its normal position. The action of the pins 22^a upon the lever 20^a in co-action with the force of gravity thus produce a rising and falling of the figure 24^a which is extremely amusing and entertaining to the child.

The actuating mechanism illustrated in 30 Fig. 5 shows a combination of the two forms previously described and indicates how the invention may be further developed to produce predetermined effects and combinations of effects. The spaced disks 23^a mounted 35 upon the axle 14 in addition to carrying the pins 22^a, as in Fig. 3, carry also a pair of pins 22^b corresponding to the pins 22 of Figs. 1 and 2. With this arrangement of 40 actuating mechanism a toy comprising a combination of the two previously described is possible or said actuating mechanism may be utilized to bring about movements of components otherwise arranged on the body.

The essentials of the present invention 45 may be said to comprise a lever operatively connected with a figure located above the top of the body and either heavy enough by its own weight or otherwise weighted to always return to its normal position by 50 gravity, in combination with a wheel draft, and driven mechanism including pins for periodically engaging said lever to impart a motion to the figure and then passing out of the way of said lever to permit the figure 55 to reassume its normal position. These essentials may be arranged in any number of different combinations as will be readily apparent.

The toy in all of its forms is simple in 60 construction and need contain no metal parts whereby the child may be injured, the illustrating examples showing toys constructed substantially entirely of wood.

The toy may be constructed to include any type of figures movable to simulate different natural movements and may be grotesque and funny or otherwise as desired. 65

Various changes in the specific forms shown and described may be made within the scope of the claims without departing 70 from the spirit of my invention.

I claim:

1. A toy comprising a supporting body, an axle rotatably mounted thereon, wheels carried by said axle, a figure pivotally mounted upon the body and movable in a vertical plane, said figure being capable of returning to its normal position by gravity, a lever operatively connected with said figure and extending downwardly therefrom and actuating mechanism mounted upon said axle and rotatable in a plane parallel with the planes of rotation of said wheels whereby said lever is periodically actuated to operate said figure and to permit it to 85 resume its normal position by gravity. 80

2. A toy comprising a supporting body, an axle rotatably mounted thereon, wheels carried by said axle, a figure pivotally mounted upon the body and capable of returning to its normal position by gravity, a lever extending downwardly from said figure beyond said axle, a disk fixed upon said axle and rotatable therewith and a pin projecting from the face of said disk to periodically engage said lever whereby said figure is actuated in one direction and to relieve said lever whereby said figure is actuated in a return direction by gravity; said axle forming a stop for said lever whereby 100 said return movement of said figure is arrested. 90

3. A toy comprising a hollow body, an axle journaled on the same, wheels secured upon said axle, a plurality of movable figures mounted upon said body and projecting above the same, levers pivotally mounted upon said body and connected with said figures, said levers extending into said body, a disk fixed upon said axle and arranged to partake of the rotative movements of said wheels and pins projecting in opposite directions from said disk and arranged to periodically swing said levers whereby said figures are actuated and to relieve said 110 levers whereby said figures are permitted to reassume their normal positions by gravity, said levers when relieved engaging said axle with audible impacts to simulate predetermined effects in accordance with the characteristics of the originals represented by 115 the figures. 120

In testimony whereof I have hereunto set my hand.

SOMA HERZOG.
